H. A. SKIPWORTH

SAFETY RAZOR

Filed Aug. 31, 1922

INVENTOR:
Harry A. Skipworth,
By
Atkins & Atkins,
ATTORNEYS.

UNITED STATES PATENT OFFICE.

HARRY A. SKIPWORTH, OF PORTLAND, OREGON.

SAFETY RAZOR.

Application filed August 31, 1922. Serial No. 585,368.

To all whom it may concern:

Be it known that I, HARRY A. SKIPWORTH, a citizen of the United States of America, and resident of Portland, in the county of

5 Multnomah, in the State of Oregon, have invented certain new and useful Improvements in Safety Razors, of which the following is a specification, reference being had to the accompanying drawing.

10 My invention relates to that class of razors known as safety razors, and has for its object the production of such a razor which is comparatively cheap and simple but effective in construction, whose parts may be 15 easily disassembled for cleaning and sharpening, whose blade is preferably of the hollow-ground type of the ordinary razor, and whose handle is readily convertible and adapted to be used either with a guard for 20 shaving or without the guard for sharpening and keeping the bared blade in fit condition for use.

What constitutes my invention will be hereinafter specified in detail and succinctly 25 set forth in the appended claims.

In the accompanying drawing,

Figure I is a side elevation of my invention in present preferred form of embodiment complete, the blade and its guard being shown in end view, the contents of the hollow handle being shown in dotted lines.

Figure II is a plan view of Figure I taken at right angles thereto, and looking at it from above.

35 Figure III is a side elevation of a portion of the hollow handle detached from the guard and showing its screw hub reversed to present to view the stopper-blade-holder, with the blade partially introduced into it.

40 Figure IV is a side elevation of my razor guard detached, looking at it from the side to which the handle is attachable, and showing in dotted lines the spring clips which serve to hold the blade in place against the opposite side of it.

45 Referring to the numerals on the drawing, 1 indicates a razor blade of any suitable shape and dimensions, but preferably of the hollow-ground type. Fitting the blade 1 at all points is a guard substantially of the kind common to safety razors, except in respect to certain distinctive differences as specified. It is preferably made of one piece of suitable spring metal so as to include a row of teeth 3 of any usual or preferred shape. The back, also, of the guard, towit,

that portion of it that is disposed on the edge of it opposite to the row of teeth 3, is provided with two spring clips 4 and 5 shaped so as to fit snugly against the face 60 of the blade 1, when they are bent into final shape towards one side of the guard as shown, for example, in Figure I.

Between the said clips the back of the guard is provided with a medial handle-plate 6 which is bent towards and in operative juxtaposition to the opposite side of the guard from that towards which the clips 4 and 5 are bent. In the manufacture of 65 my guard and in its parts appurtenant 70 thereto as just described, a flat blank is made and cut or otherwise fashioned into desired shape to form the teeth 3 and the several members 4, 5, and 6. Afterwards the teeth may be, if desired, bent to curvature as 75 shown in Figure I, and the remaining members bent to shape as described and as shown also in that figure. The metal of the guard, it being preferably made of spring steel, is then properly tempered to give to it requisite hardness, and to give to the clips 4 and 5 the resilient degree of stiffness desired. If preferred the guard may be finished with 80 a surface of silver or other plating.

85 It should be observed that the guard, as is shown clearly in Figure I, is made for the purpose specified below of varying thicknesses in respect to its several parts or members. The part 7 from which the clips 4 and 5 and the plate 6 extend and which may 90 be designated its backbone, is of a maximum thickness such as will be sufficient to impart to its union with the plate 6, which is preferably of corresponding thickness, a rigid and unyielding stability. To each of the 95 clips 4 and 5 a substantially corresponding thickness, may be imparted throughout so much of their longitudinal extent as is necessary to form in each an arch 8. Beyond that arch from an angle 9 which bounds it 100 on one side each clip is slightly tapered in cross-section or thickness so as to render the clip terminals at the same time stiff but resilient. The guard portion proper of the 105 guard or that plate 10 which is disposed between the clips 4 and 5 and the handle plate 6 as illustrated in Figure I is imperforate and is made of such thickness of metal as may impart to the said plate a degree of resiliency which will permit it to yield under 110 compulsion of an impinging screw 11 which is threaded through an aperture provided

for its accommodation in the rigid plate 6. The nose 12 of the screw 11 is rounded and makes impingement against that slight concavity in the plate 10 that is conformable to 5 the shape of the blade 1, with the effect of driving the entire plate 10 bodily towards the clips 4 and 5 in such manner as positively to lock the blade in place between the 10 said plate and the said clips, the degree of resiliency of the clips being such as to prevent possibility of any breaking strain upon the blade.

At the same time the combined presence of the guard, the blade, and the clips 4 and 15 5, opposes resistance to the advance of the screw 11 through its threaded aperture in the plate 6, sufficient to jam the threads of the screw into the threads of said aperture with nut-lock effect upon the screw.

20 The screw 11 is preferably terminally and coaxially carried upon one end of a hub of greater diameter than the screw and is provided with two externally threaded portions 14 and 15, separated by a projecting intermediate zone 16, disposed between them.

Each of the portions 14 and 15 is threaded to fit the internally threaded open end of a hollow handle 17, which is thereby adapted to be screwed upon either end of the hub and into close abutment against the zone 16 which, in either instance, acts as an annular stop-piece to the handle. The threaded portion 14 of the hub terminates in the screw 11 already described while its portion 15 terminates in an oppositely extending blade-holder consisting of a shank 18 and a pair of spring clips 19 and 20 adapted to receive and hold the back of the blade 1 between them, after the manner of blade holders familiar in the art, and therefore, in view of the illustration made in the drawing, unnecessary to describe more in detail.

40 The transverse dimensions of the blade-holder are such as to adapt it to fit easily within the hollow of the handle 17, which constitutes a case or covering for it while the razor is being used for shaving.

The following is a brief description of my 45 razor and its method of manipulation in use.

50 Assuming that the hub and handle 17 are assembled as shown, for example, in Figure

I, the operator takes in hand the naked guard as shown in Figure IV and slips into it, endwise, the blade 1. This is easily accomplished because of the loose fitment provided between the blade and the clips and plate 10 of the guard. After the blade is in place in the guard, the screw 11 is inserted into the threaded aperture provided for it in the plate 6 and is screwed into place until, in 60 the manner previously described, the end of the screw impinges against the plate 10 with the simultaneous effect of fastening the blade 1 and of locking the screw 11 in place, respectively. After shaving, the screw 11 65 being loosened, the blade 1 may be readily removed from the guard. Then, upon separating the screw 11 from the plate 6, the handle 17 may be unscrewed from the hub, the blade-holder withdrawn, and by reversal 70 of the hub the blade-holder is made ready for reception of the blade for honing or stropping purposes in the usual manner.

What I claim is:

1. A safety razor comprising the combination of a blade, a guard formed in one piece with a yielding plate, blade retaining means upon one side thereof and a rigid handle-plate upon the other, and a separable handle having a terminal screw, fitting a threaded aperture provided for it in the handle-plate and operable to force said plate against the blade with the effect specified. 75

2. A guard for a safety razor consisting of the combination of an integral member of varying thicknesses, comprising a handle-plate of sufficient thickness to render it rigid, and blade retaining means, with a plate between said means and handle-plate of diminished thickness so as to render it yieldingly 80 resilient relatively to the rigid handle-plate, whereby a member operatively mounted on the handle-plate may be made to actuate the resilient plate with the blade-holding effect 85 described. 90

In testimony whereof, I have hereunto set my hand in the presence of two subscribing witnesses.

HARRY A. SKIPWORTH.
